UNITED STATES PATENT OFFICE.

ZECHARIAH M. HOWELL, OF OCEANPARK, CALIFORNIA.

GARBAGE-WAGON.

1,116,284.

Specification of Letters Patent.

Patented Nov. 3, 1914.

Application filed February 17, 1913. Serial No. 748,963.

To all whom it may concern:

Be it known that I, ZECHARIAH M. HOWELL, a citizen of the United States, residing at Oceanpark, in the county of Los Angeles and State of California, have invented certain new and useful Improvements in Garbage-Wagons; and I do hereby declare the following to be a full, clear, and exact description of the invention, such as will enable others skilled in the art to which it appertains to make and use the same.

My invention pertains to garbage handling mechanism, and it has special reference to means whereby the garbage may be disposed of in an efficient and sanitary manner.

The object of the invention is to furnish a vehicle which carries thereon a compressing and separating mechanism, whereby the solid constituents of the garbage will be solidified, and the liquid portion separated, so that it may be discharged into the sewer at intervals, and the comparatively dried and solidified matter so condensed that the conveyance will be able to collect a much greater amount than otherwise, and the mechanism for doing the work is driven by the wheels of the conveying vehicle, as it moves from place to place, as will now be set forth in detail.

In the accompanying drawings, Figure 1 is a side elevation of my sanitary garbage wagon. Fig. 2 is a top view of the wagon. Fig. 3 is a central, vertical longitudinal section of the wagon. Fig. 4 is an enlarged side view of the roller compressing mechanism. Fig. 5 is a section of the rollers. Fig. 6 is a view of the opposite ends of the rollers, and Fig. 7 is a side view, enlarged, of the mechanism for controlling the discharge door.

In carrying out my invention, I may use a power truck for carrying the mechanism and receptacles, but in this case I show a vehicle which is to be drawn by horses, and it comprises an elongated body, 8, mounted on fore and aft wheels, 9, 10, respectively. This body is divided into three compartments, the forward compartment, 11, having its fore and aft ends sloping, as at 12, 13, these sloping walls projecting down below the main portion of the body, the terminals of the walls being separated, so as to form a discharge opening, 14. This opening is provided with a downwardly

swinging door, 15, hinged at its forward edge, as at 16, to the margin of the wall, 12. The forward edge of this door has at each end of the door a link, 17, hinged thereto, the upper end of each link being provided with a rack, 18. Alongside of the rack is a cross shaft, 19, journaled to the body, 8, one or both ends having a crank, 20. A pinion, 21, on each end of the shaft, 19, meshes with the rack, so that by turning the crank, 20, the door, 15, will be closed or opened.

The rear compartment, 22, has at its rear end a discharge faucet, 22', the bottom, 23, of the compartment being sloping so that any liquid within the compartment may be readily discharged. The upper end of this compartment has an inclined floor, 24, which extends down toward the upper edge 75 of the wall, 13, the space, 25, within the body above the inclined floor, and which is the third compartment, being designed for use as a hopper to receive the garbage. The floor 24 is removably supported upon the 80 strips 24' and is prevented from sliding downwardly by means of suitable hooks 24'', which engage the rear wall of the wagon. If desired, the floor 24 may be perforated, as shown in the drawings, to 85 facilitate the passage of the liquid into the compartment 22.

At the juncture of the floor, 24, and wall, 13, I mount a pair of transverse rollers, one above the other, the lower roller, 26, having 90 its shaft projecting at each end beyond the body, and on one or both ends it is provided with a sprocket wheel, 27, which carries a sprocket chain, 28, that extends down and over a sprocket wheel, 29, attached to 95 the rear drive wheel, 10. The upper roller, 30, has its axis journaled in sliding boxes, 31, which boxes slide within slotted yokes, 32, secured to the body, 8. Within the upper ends of each yoke is a sliding block, 33. 100 Between the block, 33, and box, 31, is a coiled spring, 34, and a threaded stem, 35, passes through the head of the yoke, 32, with its end in contact against the sliding block, so that a tension may be exerted 105 downwardly on the roller, 30. For this purpose the threaded stem has a hand wheel, 36. The projecting end of each roller shaft carries at one end a star wheel, 37, which intermesh, so that the lower roller will turn 110 the upper roller at all times, however much the two rollers may be separated by the gar-

bage which is passing through. The rollers, 26, 30, may be made of any suitable material, either rigid or elastic in their character without departing from the spirit of 5 my invention.

It is obvious that the liquid expressed from the garbage, as it passes through the roller, will be discharged into the second compartment, 22, and the partially dried 10 and solidified garbage will be deposited in the first compartment, 11, to be finally discharged through the opening, 14, when the compartment is filled. The operation of compressing the garbage and extracting the 15 water therefrom takes place when the vehicle travels from one garbage receiving point to the next, and when the vehicle passes the available sewage receptacles or openings at the street intersections, the 20 liquid within the compartment, 22, is discharged, thereby obviating the necessity of transporting the moisture of the sewage to the dumping place. As the liquid is expressed from the sewage matter, the solid 25 portion or residue can be more readily taken care of and is in condition whereby it can be preserved for a greater length of time, and in that condition its bulk is much less than if it carried the water usually contained therein.

It is obvious that instead of mounting the expressing mechanism on a vehicle, I may mount it on a base, and connect the dis-

charge faucet with a sewer, without departing from the spirit of my invention.

35

What I claim as new, is:

A garbage wagon comprising an elongated body, said body provided with a plurality of compartments, a forward compartment provided with inclined bottom walls converging toward each other at the bottom of the body, said compartment provided with an opening adjacent the lower edges of the inclined bottom walls, a door hingedly secured to one end of said opening, means for opening and closing said door, an inclined wall detachably secured to the upper rear end of said body and extending downwardly and inwardly and being disposed at its lower end adjacent but spaced from the upper end of one of said inclined bottom walls, a roller rotatably mounted between the last mentioned inclined bottom walls and within the space between said last named walls, an adjustable roller rotatably mounted above the roller and the inclined wall and in spaced relation to the first mentioned roller, means for adjusting said adjustable roller, and means for rotating said roller.

50

In testimony whereof I affix my signature in presence of two witnesses.

ZECHARIAH M. HOWELL.
